FIG. 7

INVENTOR:

CHARLES A. HUMPHREYS,

BY Cheever & Cox
ATTYS.

UNITED STATES PATENT OFFICE.

CHARLES A. HUMPHREYS, OF CHICAGO, ILLINOIS.

TIP FOR BELTS AND STRAPS.

1,405,516.

Specification of Letters Patent. Patented Feb. 7, 1922.

Application filed October 18, 1920. Serial No. 417,588.

To all whom it may concern:

Be it known that I, CHARLES A. HUMPHREYS, a citizen of the United States, residing at Chicago, in the county of Cook and 5 State of Illinois, have invented a certain new and useful Improvement in Tips for Belts and Straps, of which the following is a specification.

My invention relates to tips or end pieces 10 for belting, particularly leather straps for men's wear. The general object of the invention is to provide a piece which will be neat and compact in distinction to being bulky, and which may be easily and firmly 15 fastened to the belt. Another object is to provide a device of this character which may be readily formed from a single piece of sheet metal.

I obtain my objects by the construction 20 illustrated in the accompanying drawings, in which—

Figure 1 is a face view of a blank, prior to the cutting or forming operation;

Figure 2 is the view of a blank after it 25 has been cut;

Figure 3 is a view similar to Figures 1 and 2, but showing the device after it has been cut and formed;

Figure 4 is an end view looking towards 30 the left in Figure 3;

Figure 5 is an edge view looking upward in Figure 3;

Figure 6 is a perspective view of the finished device, and

Figure 7 is an edge view of the device, 35 shown in position in a belt and illustrating the manner in which it may be hooked to a gripping device or buckle.

Figure 8 is a perspective view of the end 40 of a "solid" belt, split at the end for the insertion of the plate or body of the end piece.

Like numerals denote like parts throughout the several views.

Referring first to the blank shown in Figure 1, this is simply a short, rectangular strip of sheet metal ready for cutting or punching. After the blank is obtained, it 45 is first punched or cut as illustrated in Figure 2. The plate portion 1 has its corners 2 cut in order to obtain what may be termed a "rounded" effect. At the same time a hole 3 is punched in the plate to accommodate a rivet or other appropriate fastening device. With the same operation, two cuts 4 are made, their shape being such as to form

two inward turned branches 6 on opposite sides of a neck 5. The next operation is to form the device, and in the forming operation, the cut blank is bent in such manner 60 that the branches 6 are raised or offset so as to lie near to but spaced from the outside of the belt, to form hooks facing inward along the belt. A second bend 8 is formed at the end of the blank, but this bends in 65 the opposite direction and by preference lies contiguous to the surface of the belt. It extends the full width of the blank, which in practice equals substantially the full width of the belt. The result is that the 70 bend 8 forms a ferrule or finishing strip for protecting the end of the belt and holding the engaged portion down close upon the body or tongue portion 1 of the blank.

In practice, the device may be used with 75 so-called "tubular" belts 10, that is, belts of double thickness but with the two thicknesses lying flat in contact with each other, as illustrated in Figure 7. Also the device may be used with so-called solid belts 80 consisting of a single piece 16 of leather as shown in Figure 8. In such case the end of the belt will be split as illustrated. Also the device may be used with so-called "lined and stitched" belts which are simply belts 85 of two or more ply, lined or unlined, and stitched together. These various types are well known in the trade. In any event, the end of the belt will be of more than one thickness and, in assembling, the ends of the body 90 portion or plate 1 of the blank is simply inserted into the open end of the belt. It is inserted far enough to bring the ferrule portion 8 close to the end of the belt to form a protection and finishing piece for it, and 95 when thus assembled a rivet 12 or other appropriate fastener is passed through the belt and through the aperture 3 in the plate, thus holding the parts securely together. As the plate or body of the device is, or 100 should be, fully equal to the inner dimension of the belt, a single rivet will be sufficient, lateral play of the device being prevented by the belt itself. In other words, the plate 1 fits snugly into the belt and will be securely fastened as soon as the rivet is in 105 place.

The hooks 6 lie adjacent to, but slightly spaced from, the side of the belt opposite to the ferrule 8 and as the tops of the hooks 110 6 preferably bend slightly upward as illustrated, a bail 14 on any desired form of belt

engaging means 15 may be readily hooked into engagement.

It will be evident that this device is of extremely simple form and is most readily manufactured. Also that it may be securely held in place and prevented from moving in any direction when a single fastening device such as the rivet 12 is employed. It will also be evident that a belt employing this device will present a very neat appearance, for the reason that the belt is not bent backward upon itself in any way, nor is any stitching required; the body of the device is simply inserted into the open end 10 of the belt and the thickness of the belt is not increased to any appreciable degree. The ferrule 8 extending as it does across the entire width of the belt, forms perfect protection for the lower or inner side of the belt, while the hooks or branches 6 which occupy a considerable proportion of the entire width of the device, perform the same office for the upper side of the belt, and at the same time, form points of attachment for 20 the belt fastener which is typified in the drawings by the device 15. Thus, by using my device, the expense of manufacture is greatly reduced, the appearance of the belt is greatly improved, its wearing qualities 30 are improved by reason of the protection which the device affords to the end of the belt, and the fastening device such as 15, may be readily connected and disconnected.

Having thus described my invention, what 35 I claim as new and desire to secure by Letters Patent is:

1. A device of the class described having a plate for insertion between the two sides of the belt, integral hooks partially severed 40 from the plate and extending backward approximately parallel to said plate and

adapted to lie on the outside of the belt and spaced from it, the outer end of the device being bent in the opposite direction to form a ferrule for the opposite side of the belt. 45

2. An end piece for tubular belts having a plate for insertion between the two sides of the belt, a neck surmounting the plate, and a head supported by the neck, the head having hooks at the two edges of the neck 50 extending backward approximately parallel to the neck on one side of it and the head having a ferrule bent backwards approximately parallel to the neck on the other side of it to form a ferrule for its side of the 55 belt.

3. A cut sheet metal blank adapted to form the end piece for a belt, the blank having a plate with two inward extending branches cut from opposite edges, the 60 branches terminating short of the outer end of the plate to thereby afford material which may be reflexed to form a ferrule extending substantially the full width of the belt.

4. A device of the class described composed of a single piece of sheet metal cut and configurated to form a plate at one end adapted to be inserted between two thicknesses at the end of a belt, said plate being adapted to be attached to the belt and being 70 approximately of the full width of the belt, the outer end of the sheet metal having a return bend adapted to form a ferrule for enclosing and protecting one thickness of the belt at one end thereof, and two reversed 75 branches at the lateral edges of the plate, spaced from each other, and bent to form hooks, substantially as described.

In witness whereof, I have hereunto subscribed my name.

CHARLES A. HUMPHREYS.
